HAIR SPRAY SHIELD OR SIMILAR ARTICLE

Stanislau Kurianski, 24040 Gunther Road,
Romoland, Calif. 92380

Filed Dec. 7, 1970, Ser. No. 26,309

Term of patent 14 years

Int. Cl. D28—03

U.S. Cl. D86—10

FIG. 1 is a front elevation of a hair spray shield showing my new design.

FIG. 2 is a rear elevation of the hair spray shield.

FIG. 3 is a side elevation of the hair spray shield, the opposite side being a mirror image thereof.

FIG. 4 is a top view of the hair spray shield.

FIG. 5 is a bottom view of the hair spray shield.

I claim:

The ornamental design for a hair spray shield or similar article, substantially as shown and described.
